JOHN M. ENOS, OF ST. JOSEPH, MICHIGAN.

Letters Patent No. 61,819, dated February 5, 1867.

IMPROVEMENT IN STEAM ENGINES.

The Schedule referred to in these Letters Patent and making part of the same.

TO ALL WHOM IT MAY CONCERN:

Be it known that I, JOHN M. ENOS, of Saint Joseph, in the county of Berrien, and State of Michigan, have invented a new and useful Improvement in Steam Engines; and I do hereby declare and make known that the following is a full, clear, and exact description of the same, reference being had to the accompanying drawings, and the letters and figures marked thereon, which form part of this specification.

My said invention consists in arranging, at one end of the steam cylinder, a steam generator, as herein-after more fully described, into which generator only enough water to generate the amount of steam necessary to give the piston a single stroke, is injected at one time, thus dispensing with large generators and obviating all danger of explosions, the steam at the same time acting directly upon the piston, thus greatly economizing the power thereof. My said invention further consists in so arranging the steam generator in relation to the furnace which heats the same, that that part thereof into which the water is introduced as aforesaid, may be heated less than the remaining part, so that the water introduced may be readily converted into steam, which then passes into the more heated part of the generator to be converted into superheated steam before entering the cylinder to operate the piston. My said invention further consists in a novel arrangement within the steam generator for preventing the injected water from coming in contact with the surface of the generator, thus preventing the incrustation thereof, and preserving it from the injurious effects of sudden expansion and contraction, and at the same time affording a much greater heating surface to act upon the water to convert it into steam, and upon the steam to superheat it; while from the fact that said arrangement is removable, it affords a ready and simple mode of cleaning out the generator and removing all incrustations.

To enable those skilled in the art to understand how to construct and use my said invention, I will proceed to describe the same with particularity, making reference in so doing to the aforesaid drawings, in which—

Figure 1 represents a front elevation of my invention.

Figure 2, a plan or top view of the same.

Figure 3 is a horizontal central sectional view thereof.

Figure 4, a transverse sectional view at the line z , in fig. 1; and

Figure 5 is a transverse section of the steam cylinder at z , in fig. 3.

Similar letters of reference in the several figures denote like parts of my said invention.

A represents a suitable enclosure for the furnace, which is marked K, within which enclosure, and above the furnace, as shown, is arranged a reservoir for water, marked R, and within which enclosure also is arranged the generating chamber or cylinder, marked B, as shown in figs. 3 and 4 in the aforesaid drawings. The water is pumped into the reservoir in any suitable manner, and is thence injected into the generator by any suitable means, through the pipe I, which passes through a removable head upon said generator, as shown, and is provided upon its end with an arrangement for dispersing or diffusing the water so as not to fall in a mass or body upon the heated surfaces within. Within the said generator is arranged a cast-iron or other suitable metallic cylindrical vessel, marked E, into one end of which enters the pipe I, as shown, and in the other end of which there is a suitable outlet, as shown in fig. 3. The said cylinder has exterior projections to prevent its lying upon the generating cylinder B, thus leaving an annular space between the generator and said removable cylinder E, as shown. Within the said cylindrical vessel E, is arranged one of similar configuration, marked F, having perforated walls, as shown, and having between it and E a space, as shown. This perforated cylinder is readily removed from the cylinder E by removing the outer end of said cylinder E, which is made removable for that purpose. It will be observed that the said steam-generating cylinder extends outside of the furnace, while the interior end is within the furnace, so that the heat will be less intense at the outer end in which the aforesaid removable metallic cylinders E F are placed, and into which the water is injected, than at the other end of the cylinder, represented by B', into which the steam passes in entering the steam cylinder C, which is arranged at the end of the generator, so that the steam in entering said cylinder has a direct action upon the piston, avoiding all loss of power by friction, and all condensation which would result from passing the steam through pipes before it enters the said cylinder. The steam cylinder C, as shown, is attached to or arranged with the generator, so as in a certain sense to form a part of the same, and yet in such a manner as to be detached and removed from it, so that in case of either getting out of repair it may be replaced without disturbing the

other part. Between the generator and cylinder there is a port, *d*, at one end, and a port, *e*, at the other, the one opening directly into the cylinder, and the other being connected with the generator by means of a pipe, *G*, as shown. These ports are opened and closed alternately by means of a shaft, *L*, having transverse grooves or passages *b c*, at right angles with each other, at the points where the shaft *L* cuts the ports, as shown. The said shaft is provided at one end with a crank and arm, *M*, connected with the machinery of the engine in such a manner as to give a suitable rocking movement to the shaft, which has the effect to operate the valves in the ports as desired. At each end of the said cylinder *C* are exhaust ports, *g f*, opening into an escape pipe, *H*, as shown, having suitable cut-offs, *h i*, operated to open and close said exhaust ports as desired, by means of the said rocking movement of the shaft *L*, to which said cut-off slides are suitably connected. Instead of the arrangement for opening and closing the several ports above named, any other suitable valves or slides may be used. At that side of the enclosure *A* at which the steam cylinder connects with the generator, there is a narrow space marked *A'* left, having openings, *a*, at the front and rear, so as to allow and induce a current of cold air through the same and about the cylinder, to prevent the cylinder *C* from being over-heated by the action or effect of the fire in the furnace. When there is no steam in the generator the engine must, or may, be started by injecting a sufficient amount of water into the generator by means of a hand-pump; but as the generator should be made of sufficient size to contain steam enough to produce two or three strokes of the piston, this will be unnecessary after any temporary stoppage of the engine.

Having described the nature and construction of my invention, I will proceed to describe its operation. The fire being started in the furnace, and the generator sufficiently heated, the water is injected in suitable quantities into the generator, and being dispersed upon the interior of the perforated cylinder *F*, is at once converted into steam. If it should happen that all the water should not be converted into steam within said perforated cylinder, passing through the said perforations, it would come in contact with the close cylinder *E*, and there all water which was before unconverted would be changed into steam, and then the whole body of the steam would pass on into the chamber *B'*, more intensely heated, and be superheated. The superheated steam filling the space between the walls of the generating cylinder and the cylinder *E*, serves to heat the said cylinder *E* and make it more effectual in its operation in vaporizing the water coming in contact with it as aforesaid. Thus it will be observed that no water comes in contact with the surface of the generating cylinder, and hence there are no sudden changes of temperature to injure it, and no injury can result from incrustation, as all contraction and expansion arising from the contact of water, and all incrustations arising from the same cause, occur upon and in the removable cylinders *E* and *F*, so that all repairs and cleaning out are effected by removing said cylinders, or one of them, and removing the incrustation, or replacing them with new ones. The steam having been superheated, as aforesaid, passes through the port *d*, and the exhaust port *g* being closed, moves the piston back to the position indicated in fig. 3. Just at this point the movement of the shaft *L* closes the exhaust port *f* and port *d*, and opens the port *e*, and exhaust port *g*, so that the steam entering the cylinder at *e* forces the piston back to its original position, and so on as long as the engine may be in operation. Instead of using a single steam cylinder, and admitting the steam into both ends, as herein described, two cylinders with corresponding generators may be used, thereby obtaining the direct action of the steam upon the piston in both movements. Dampers may be arranged in the furnace or smoke pipe for the purpose of regulating and controlling the heat if desired.

Having described the nature, construction, and operation of my aforesaid invention, I will now proceed to specify what I claim as new and desire to secure by Letters Patent:

1. I claim the arrangement of the generating cylinder or chamber, with the steam cylinder of a steam engine, when connected by one or two ports, and operating substantially as and for the purposes set forth.
2. I claim the arrangement within the generator of one or more removable cylinders, *E F*, substantially as and for the purposes specified.
3. I claim the arrangement of the generator with respect to the furnace in such a manner that after the water is converted into steam in one part thereof, said steam passes through an intensely heated chamber and becomes superheated in its passage into the steam cylinder, substantially as specified.
4. I claim the arrangement of the cold-air passage *A'*, with respect to the generator and steam cylinder, substantially as and for the purposes described.

JOHN M. ENOS.
